Primary Examiner — Karen E Eldridge Powers

CLAIM

The ornamental design for a power scrubber, as shown and described.

DESCRIPTION

FIG. 1 is a front, left and top perspective view of a power scrubber showing my new design;

FIG. 2 is a right, rear and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof showing the power scrubber in an environment in which it may be used;

FIG. 10 is a perspective view thereof showing the power scrubber in another environment in which it may be used;

FIG. 11 is a perspective view thereof showing the power scrubber in another environment in which it may be used; and,

FIG. 12 is a perspective view thereof showing the power scrubber in another environment in which it may be used. The broken lines in the Figures illustrate portions of the power scrubber and environment that form no part of the claimed design.
